UNITED STATES PATENT OFFICE.

CHARLES A. BARROW, OF CHICAGO, ILLINOIS.

SHIELD FOR SAD-IRONS.

SPECIFICATION forming part of Letters Patent No. 788,697, dated May 2, 1905.

Application filed January 15, 1904. Serial No. 189,156.

To all whom it may concern:

Be it known that I, CHARLES A. BARROW, a citizen of the United States, residing at Chicago, in the county of Cook and State of Illinois, have invented certain new and useful Improvements in Shoes for Sad-Irons; and I do hereby declare the following to be a full, clear, and exact description of the invention, such as will enable others skilled in the art to 10 which it appertains to make and use the same.

My invention relates to a novel construction in a shoe for sad-irons, the object being to provide a device which is adapted to receive the sad-iron, be heated thereby, and the 15 lower face of which is smooth and polished, so as to be passed over the fabric, such face remaining smooth and clean by reason of the fact that it is not placed upon the fire and is accordingly not subject to taking up soot or 20 dirt.

A further object is to provide a shoe which is very easily and quickly secured to the sad-iron and firmly held in place thereon; and it 25 consists in the features of construction and combinations of parts hereinafter fully described and claimed.

In the accompanying drawings, illustrating my invention, Figure 1 is a vertical longitudinal section of a shoe for sad-irons constructed 30 in accordance with my invention and showing a sad-iron in place therein. Fig. 2 is a top plan view of a sad-iron having a shoe constructed in accordance with my invention mounted thereon. Fig. 3 is a detail vertical 35 section on the line 3-3 of Fig. 2.

My said device consists of a sheet-metal receptacle having the general contour of the ironing-face of the sad-iron and corresponding very nearly in size with the latter. The said receptacle consists of the bottom plate A, provided with a peripheral flange B, the latter being extended adjacent the ends and merging into two integral standards C and D. The said standard C is adapted to be turned over at its 45 upper end to form a pivot for the U-shaped fastening device E, while the standard D is provided with two outwardly-extending projections F, provided in their lower edges with recesses G, forming hooks in which the free 50 ends of said fastening device are adapted to

be received and held. The said fastening device E consists of a U-shaped wire, the central part of which is held in the overturned end of said standard C and forms a pivot upon which the same turns, while the free ends 55 thereof project beyond the standard D and are provided at their ends with knobs H, preferably of wood or other non-conducting material, which may be easily handled by the operator without danger of burning 60 the fingers. Between the pivot portion and said free ends the said wire is provided with two spiral loops J, forming interposed springs which are projected downward to bear upon the middle portion of the upper face of the 65 sad-iron on each side of the handle K thereof, so that when said free ends have entered the said recesses in the lower edges of said projections on said standard D the said loops J will exert a yielding pressure on the sad-iron, and thus hold said shoe firmly in place 70 thereon. My said shoe may obviously be made to conform in shape and size with various sad-irons, and, as will be obvious, the iron is very easily inserted and removed, as it 75 is only necessary that the operator press down upon and separate the knobs at the free ends of the fastening device, thereby releasing same from engagement with the projections of the standard D and then throw the 80 same entirely over out of the path of the sad-iron. The latter is thereupon lifted out of the shoe and another iron inserted in place thereof.

I claim as my invention—

1. A shoe for sad-irons, comprising a receptacle adapted to receive the sad-iron and carrying a fastening device, said fastening device comprising yielding bars disposed longitudinally relatively to said shoe, said bars 90 being bent between their ends so that the middle portion thereof projects downwardly and bears upon the upper face of the sad-iron, and means for removably holding said bars in engagement with said sad-iron. 95

2. The combination with a sad-iron, of a shoe adapted to receive the same, said shoe comprising a receptacle provided at its ends with uprights projecting beyond the upper surface of said sad-iron, fastening means piv- 100

otally secured to one of said uprights, yielding projections interposed between the ends of said fastening means and adapted to bear upon the upper surface of said sad-iron, and 5 devices carried by the other upright adapted to receive and engage the free end portions of said fastening means to hold the latter in yielding engagement with said sad-iron.

3. A shoe for sad-irons comprising in combination a receptacle adapted to receive the sad-irons, uprights at either end of said receptacle, a U-shaped bar pivotally mounted at its central portion on one of said uprights and having its arms extending longitudinally 15 on each side of the handle of the sad-iron, and projecting beyond the other of said uprights,

said arms being bent between their ends to form spiral coils projecting downwardly and adapted to bear upon the upper face of said sad-iron, projections on each side of the other of said uprights having recesses in their lower edges adapted to receive the free end portions of said arms, and knobs of a non-conductant material mounted on the free ends of said arms. 20

In testimony whereof I affix my signature in presence of two witnesses.

CHARLES A. BARROW.
